ATTORNEY

UNITED STATES PATENT OFFICE.

HERMAN MATZEN, OF BEDFORD, OHIO.

DESIGN FOR A CHAIR-BACK.

SPECIFICATION forming part of **Design No. 18,833, dated January 1, 1889.**

Application filed November 5, 1888. Serial No. 290,020. Term of patent 3½ years.

To all whom it may concern:

Be it known that I, HERMAN MATZEN, a citizen of the United States, residing at Bedford, in the county of Cuyahoga and State of Ohio, have invented and produced a new and original Design for a Chair-Back, of which the following is a specification, reference being had to the accompanying drawings, forming part thereof.

10 Figures 1 and 2 are views in perspective showing, respectively, a single chair and a double chair or settee.

15 My design relates to the back for a chair or settee. The back consists of the posts A, the transverse rails B, and the vertical spindles C, arranged between the inner or adjacent rails B.

The novel feature of the design consists in

the tie-rods D, arranged midway between the two series of spindles and extending vertically, so as to connect the series of transverse rails B. The tie-rods may terminate with the lower rail B, as shown in Fig. 2.

What I claim is—

A design for chair or settee backs, consisting of the transverse rails, two series of spindles, and centrally-arranged vertically-disposed tie-rods, substantially as herein shown and described.

In testimony whereof I sign this specification, in the presence of two witnesses, this 22d day of June, 1888.

HERMAN MATZEN.

Witnesses:

WM. O. TAYLOR,
FREDRICK ZIEHM.
